Patented Mar. 15, 1921.

W. Inventor,
Nathaniel A. De Forest,
By Almond Hall, Atty.

UNITED STATES PATENT OFFICE.

WINTHROP A. DE FOREST, OF TOLEDO, OHIO.

DOOR-OPERATING MECHANISM.

1,371,229.

Specification of Letters Patent.

Patented Mar. 15, 1921.

Application filed May 15, 1919. Serial No. 297,228.

To all whom it may concern:

Be it known that I, WINTHROP A. DE FOREST, a citizen of the United States, residing at Toledo, in the county of Lucas and State of Ohio, have invented certain new and useful Improvements in Door-Operating Mechanisms; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to and its object is to provide a simple, cheap and convenient mechanism for opening and closing folding doors, such as the doors of a garage. My invention is also designed to furnish a construction by means of which such opening and closing of the doors may be effected from a point remote from the doors.

To these ends my invention consists of the devices, construction and arrangement of parts hereinafter described, and illustrated in the accompanying drawings, in which— Figure 1 is a top-plan view of a pair of folding doors equipped with my control, and Fig. 2, an elevation of the same.

Similar characters indicate like parts in both views.

In the drawings, a pair of doors, hinged to swing inwardly, is indicated by the numerals 1—2. Upon the casing of these doors, or upon the wall, directly above the meeting line of the free edges of the doors, is rigidly secured a stout bracket 3. Upon the outer end of this bracket a horizontal lever 4, of the first class, is fulcrumed at its middle, as at 5, a fulcrum-pin 6 serving to retain the two parts in operative relation. 7—7 are brackets secured to the wall or door-casing at opposite sides of the door-opening near and just below the upper edge of the doors. To each of these brackets is pivotally secured, as at 8, one end of a lever 9, of the second class. At their other ends these levers are connected, as at 10, with one end of a connecting rod 11, the other end of which is pivotally connected, as at 12, with the lever 4, the two rods 11 being connected with opposite ends of the lever 4. The rods 11 are adjustable, as to length, by means of turn-buckles, as clearly

indicated in the drawings. The rods herein referred to may be and preferably are formed of pipes. The relation of the levers 9 and the rods 11 to the lever 4 is such that the latter lever rests normally at an angle of forty-five degrees to the plane of the doors when these are in either closed or open position.

Upon each of the doors, near its top, is secured a bracket 13 to which is pivoted, as at 14, one end of a link-bar 15, the other end of which is pivotally connected, as at 16, to the lever 9. It will be seen that the parts thus far described as connected with lever 4, are interchangeable and may be used upon either the right or left hand door. It is now manifest that the swing of the lever 4 upon its fulcrum will, through rods 11 the levers 9 and the links 15, cause the doors to swing upon their hinges either into open or closed position. This swing of the lever 4 is attained by means of the mechanism now to be described.

17 is an upright rod or tube forming a shaft which is mounted in brackets secured to the side-wall of the building, or, if preferred, stepped at its bottom in a suitable socket. At its top the shaft 17 carries a horizontal arm 18 in substantially the same horizontal plane as the lever 4. The arm 18 is pivotally connected, as at 19, with the lever 4, as at 20, by means of the longitudinally adjustable rod or pipe 21. Secured to the upright shaft 17, a convenient distance from the floor, is an arm or handle 22, by means of which the shaft 17 may be rotated, thus giving motion to the arm 18 and to the lever 4 through the connecting rod 21. It will thus be seen that by swinging the handle 22, the doors, through the connections above described, are swung upon their hinges into open or closed position.

If it is desired to operate the doors from a distant point, this may be effected by means of a rod 23 pivotally connected to the arm or handle 22, as at 24, and extending to any desired point. It will be understood, without illustration, that this rod may be either manually or mechanically actuated, and that the mechanical means may be of any suitable sort controlled by any familiar controlling devices, which, being no part of the present invention, need not be here further elaborated.

Having described my invention, what I

claim and desire to secure by Letters Patent, is—

In a door operating mechanism, in combination with a pair of hinged doors, a bracket secured above and in alinement with the meeting edges of the doors, a lever of the first class fulcrumed on said bracket, for each of said doors a stationary bracket secured near the top of the hinged edge of the door, levers of the second class fulcrumed on the latter brackets, links which pivotally connect the latter levers with the

doors, rods which pivotally connect the opposite ends of the lever first mentioned with said links, and devices for actuating said first mentioned lever, whereby the doors are simultaneously opened and closed. 15

In testimony whereof I affix my signature in presence of two witnesses.

WINTHROP A. DE FOREST.

Witnesses:

MARK WINCHESTER,
GRACE SMITH.
